UNITED STATES PATENT OFFICE

JOHN N. RASP, OF MCKEESPORT, PENNSYLVANIA

CURTAIN ROD TIP OR CURTAIN PROTECTOR

Application filed June 30, 1931. Serial No. 547,964.

This invention relates to a curtain rod tip or curtain protector, and it is an object of the invention to provide a device of this kind which, when applied to the end portion of a rod, provides effective means to facilitate the desired threading of the rod through the casing or sheathe of the curtain or other drapery.

Another object of the invention is to provide a device of this kind which may be slid upon the end portion of a curtain rod and which, when in such applied position, serves effectually to prevent the sharp edges of the rod proper cutting through the curtain and more especially when the rod is being applied to the curtain.

The invention consists in the details of construction and in the combination and arrangement of the several parts of my improved curtain rod tip or curtain protector whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a fragmentary view in perspective illustrating a curtain rod partly threaded within the sheathe or casing of a curtain with a tip or protector constructed in accordance with my invention applied to the rod;

Figure 2 is a view in side elevation of the device as herein disclosed unapplied;

Figure 3 is a view in elevation of the opposite side of the device;

Figure 4 is a view in plan of the blank from which the device is produced;

Figure 5 is a fragmentary view taken lengthwise through an end portion of a cur-

tain rod and a tip or protector applied thereto.

As disclosed in the accompanying drawing, C denotes a conventional type of curtain rod of the flat C type in cross section and which is adapted to be threaded or inserted through the casing or sheathe 1 suitably provided in a curtain or the like.

Ordinarily in threading the rod C through the sheathe or casing 1 the sharp edges of the rod C have a tendency to cut through the fabric and thus not only interfere with the desired application of the rod but materially damage the curtain. To avoid these manifest disadvantages I provide a curtain rod tip or curtain protector R which is adapted to be slid upon either end portion of the rod C and when so applied to effectively protect the fabric of the curtain against injury from the sharp edges of the rod and also to materially facilitate the threading of the rod through the sheathe or casing.

My improved tip or protector R, as herein disclosed, is formed from an elongated strip of metal of desired dimensions and which in the blank has its opposite end portions provided at one side with laterally disposed elongated wings 2 and at the opposite side at points inwardly of the inner ends of the wings 2 with the laterally disposed flat lugs 3. At the same side the strip is also provided with the smaller flat lugs 4 positioned inwardly of the lugs 3 and also inwardly of but in relatively close proximity to the inner ends of the wings 2.

The side marginal portions of the metal strip proper are inwardly disposed to provide the side walls 6 substantially equidistantly spaced from the transverse center of the metal strip proper. The opposite end portions of the strip are folded or returned to provide a substantially U-shaped member consisting of the side channel arms with the intermediate portion 7 connecting said arms disposed on a curvature from end to end and

merging with the adjacent extremities of the side arms in a manner whereby is eliminated any sharp edges or corners. This intermediate portion 7 is also of channel formation and receives the end of the rod C upon which the tip or device is applied whereby effective protection is had against such sharp edges of the rod cutting or otherwise injuring the fabric of the curtain when the rod is being threaded into applied position.

The completed device is so formed as to snugly receive between the side arms thereof the end portion of the rod C with the intermediate portion of the device outwardly disposed or directed across the end of the rod thereby providing means to facilitate the desired threading of the rod through a casing or sheathe and at the same time eliminating the liability of the fabric of such casing or sheathe being injured during such threading operation. When the device is applied to the curtain rod the wings 2 have close contact with the outer face of the rod while the flat lugs 3 are disposed inwardly to have close contact with the free longitudinal edges of the rod. The contact of the lugs 3 with the longitudinal edges of the rod serve to maintain the side arms closely adjacent to the rod and also hold said side arms when the tip is applied against any tendency of separating movement as a result of inherent resiliency possessed by the tip. The lugs 4 have close frictional contact with the free longitudinal marginal portions of the rod.

It is, therefore, believed to be clearly apparent that the construction of the tip or protector is such as to permit its ready and convenient application to the end portion of a curtain rod and also to assure the device against accidental displacement.

From the foregoing description it is thought to be obvious that a curtain rod tip or curtain protector constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A tip for a curtain rod of a flat C type comprising a U-shaped member having channel side arms to snugly receive therebetween an end portion of the rod, said side arms at one side of the tip being provided with inwardly disposed flat lugs to be extended inwardly of the rod to which the tip is applied for close contact with the free longitudinal edges of the rod.

2. A tip for a curtain rod of a flat C type comprising a U-shaped member having channel side arms to snugly receive therebetween an end portion of the rod, said side arms at one side of the tip being provided with inwardly disposed flat lugs to be extended inwardly of the rod to which the tip is applied for close contact with the free longitudinal edges of the rod, said tip at the same side thereof being provided with additional flat lugs for close contact with the adjacent face of the rod.

In testimony whereof I hereunto affix my signature.
